PROCESS AND APPARATUS FOR PREPARING COTTON FOR SPINNING.

Application filed July 26, 1926, Serial No. 124,846, and in France March 8, 1926.

This invention relates to methods and machines used in preparing cotton for spinning.

It is the chief object of the invention to improve such machinery and methods with a view to increasing their efficiency and effecting economies in the preparation of the cotton.

According to the usual practice, the slivers resulting from the carding operation are doubled and drafted until the fibres are brought into the approximately parallel relationship desired for spinning. The number of slivers which can be treated in a given machine is limited by the fact that as the number of ends is increased the number of stop motions also is increased, and since the operation of any of said stop motions stops all the deliveries of a head, the efficiency of the machine is proportionately decreased.

20 The present invention utilizes the principle that by increasing the number of fibres being drawn, it is possible to increase the draft, and consequently, to reduce the number of doublings.

25 According to the present invention a large number of slivers are wound continuously, without drawing, on a spool, roll, or core of some kind, the slivers being disposed in parallel relationship and being of equal length.

30 This produces what may be termed a "lap", the web being composed of parallel slivers. Subsequently, this web is fed through a drawing frame and the entire web is drawn simultaneously. In other words, instead of feeding a drawing delivery with a number of individual slivers, each delivery is fed with a lap made as above described. All the laps are of the same length, and the machine is so arranged that when once started it operates without stopping until the lap is exhausted.

The invention includes both a novel process and also novel machines.

The various features of the invention will be readily understood from the following description, reference being made to the accompanying drawings, in which

50 Figure 1 is a side elevation showing certain parts of a doubling machine provided by this invention;

Fig. 2 is a longitudinal, cross-sectional view through the doubling machine;

Figs. 3 and 4 are elevations showing de-

tails of the automatic stop or knock-off mechanisms;

55 Fig. 5 is a diagrammatic plan view of the doubling machine;

Fig. 6 is a diagrammatic cross-sectional view of the drawing frame provided by this invention; and

60 Fig. 7 is a plan view of the drawing frame shown in Fig. 6.

Referring first to Figs. 1, 2 and 5, it will be seen that the doubler there shown comprises a feed roll 1 cooperating with a roll or 65 guide 2 to draw strands of sliver S from cans or other sources of supply. Immediately back of the roll 1 the slivers pass over stop motion spoons 4 of the usual type, these spoons being arranged to cooperate with 70 toothed disks 5 on the stop motion shaft 6. The slivers converge to pass through guides 7, Fig. 5, and thence are fed between fluted feed rolls 8 and 9, these rolls limiting the tension on the slivers to that necessary to tip 75 the stop motion spoons as soon as the slivers begin to move. These slivers are wound in parallel relationship on a roll 10, Fig. 1, the lap thus formed resting on rolls 11 and 12 which drive the lap. The latter rolls are 80 driven by gear connections (not shown) with the main shaft 13.

It will be observed that this machine simply winds the slivers into the form of a lap without drawing or calendering them.

85 The machine is equipped not only with a stop motion which throws off the power or interrupts the drive, but also with a brake which stops the main shaft 13 immediately after the power is thrown off. This entire 90 mechanism is under the control of the spoons 4 so that if a strand or "end" of sliver should be broken, the machine is stopped before the broken end can go beyond the rolls 8 and 9. It is thus possible to bring up the sliver to 95 this end in order to preserve the continuity of the sliver without actually piecing it up.

In addition to stopping the machine automatically upon the breaking of a sliver, provision is also made for stopping it automatically 100 when a predetermined length of sliver has been wound in the lap. That is, the machine is equipped with a counting mechanism comprising the usual pinions 14 and 15, Figs. 1 and 2, the pinion 15 being mounted 105 on the shaft 16 which supports the roll

11, previously referred to, and being also geared to the pinion 14. These pinions are provided with the usual knock-off parts 14' and 15', respectively, of the so-called "candlestick" type, which cooperate when a predetermined length of sliver has been wound to force the pinion 14 away from the pinion 15.

The knock-off or stop mechanism comprises a bar 17, Figs. 3 and 4, carrying a fork 18 which is adapted to shift the belt from the fast pulley 19 to the loose pulley 20, or vice versa, this bar being mounted for sliding movement. An upright arm 21, rigid 10 with the bar, has its upper end located between two pins 22—22 secured in a bar or rod 23 which is pivoted at 24 to a lever 25. This lever swings on a fixed fulcrum 26. At the point 27 the lever 25 is pivoted to a 15 horizontal latch bar 28 provided with notches 29 and 30 which are adapted to engage with a stationary part 31 of the machine frame. A spring 32 tends to move the bar 28 toward the right, Figs. 3 and 4, and thus to shift 20 the fork 18 from the position shown in Fig. 3, where it holds the belt on the fast pulley 19, to the position shown in Fig. 4 with the belt on the loose pulley 20. This throws the power off the machine. Normally this 25 movement is prevented, however, by the fact that the notch 29 of the bar 28 engages the frame piece 31.

When one of the spoons 4 drops, due to the breaking of a sliver, the tail of this 30 spoon engages its toothed wheel 5, thus stopping the rotation of this wheel, and therefore of the shaft 6. This throws the clutch member 33, Fig. 4, toward the left, due to the inclined teeth on the clutch parts, and 35 thus swings the upper end of the bell crank lever 34 toward the left, Fig. 4, about its fulcrum 35, and causes its opposite end to lift the bar 28 far enough to disengage the notch 29 from the frame part 31. The 40 spring 32 immediately shifts this bar into the position shown in Fig. 4 and operates through the connections above described to move the belt on to the loose pulley 20.

As above stated, the operation of the stop 45 motion also sets a brake. This brake comprises a brake shoe 36, Figs. 1, 2 and 4, mounted to rock on the shaft 37 and adapted to engage the inner surface of the fast pulley 19. A handle 38 projects laterally from the 50 brake hub and normally is engaged by one arm 39 of a bell crank lever which is fulcrumed at 40 and has another arm 41 projecting upwardly and bearing against a collar 42 which is secured on the latch bar 28. So long as the belt is held on the fast 55 pulley 19, the arm 39 holds the brake handle 38 upwardly, as shown in Figs. 1 and 3, and therefore keeps the brake out of engagement with the pulley 20. But when the latch bar 60 28 is released, and the belt is shifted on to

the loose pulley 20, the lever arm 39 drops due to gravity, the handle 38 also drops, and the brake 36 is applied by gravity. This brings the machine to a stop very quickly.

For the purpose of causing the counting mechanism to stop the machine automatically, the shaft of the pinion 14, Figs. 1 and 2, extends through the upper end of a lever 44 which is fulcrumed at 45 and is provided at its lower end with a hook 46 that 70 normally supports a block or lug 47 on a lever 48. This lever is fulcrumed on the main shaft 13, and when the knock-off parts 14'—15' engage each other and force the pinion 14 toward the left, Fig. 1, the hook 75 46 is swung toward the right, thus releasing the lug 47 and allowing the left-hand end of the lever 48 to drop. The opposite end 80 48' of this lever lies between projections of a slide 50, Figs. 1, 3 and 4, so that when the 85 lever is released by the hook 46 the slide will have lifted sufficiently to cause its upper end 90 51 to engage the bar 28 and lift it far enough to disengage the notch 29 from the frame part 31. This results in shifting the 95 belt on to the loose pulley and applying the brake, as above described.

When the machine has been stopped, either by breaking of a sliver or by the operation of the counting mechanism, the belt 100 shipper or fork is locked with the belt on the loose pulley, partly by the engagement of the notch 30 of the bar 28 with the frame piece 31, and partly by the engagement of the notch 52 in the bar 23, Fig. 4, with said 105 frame piece, the latter bar having two such notches separated by a curved part 53 which offers a moderate resistance to the movement of the belt shifter from either of its 110 positions to the other. Consequently, the 115 machine cannot be put in operation again until the workman or attendant has placed the bars 23 and 28 in their proper positions.

The drawing frame comprises inclined 120 guides 55—55 for supporting a rod 56 on which the spool 10 for the lap L is mounted. The rod is provided with a collar 57 and with a grooved part 58 which limits its transverse movement but permits the lap to slide freely down the inclined bars 55 into 125 contact with the fluted feed roll or unwinding roll 59. This roll has collars 60—60 which limit the endwise movement of the lap L. As the web composed of the slivers is fed forward, it is directed by the sliver guide 61, this guide having converging sides and tapered blocks 62 and 63. The web passes between the drawing rolls 64 over another guide 65, provided with converging sides, through the trumpet 66 to the calender rolls 67—67. Between certain of the drawing rolls an edge controlling guide 68 is mounted for the purpose of preventing the edges of the lap from spreading or thinning out. This guide floats freely on the lap and 130

can be displaced with it. The upright edges of the guides 61 and 65 also control the edges of the web, the guiding parts being arranged to exert a minimum of tension on the web between the feed roll 59 and the trumpet 66. A creel 69 preferably is provided to receive a spare lap so as to reduce to a minimum the time required in replacing a lap when one is run out.

10 With my doubling machine the doubling or winding of the slivers can be performed very rapidly and with a minimum of interruption, due to the fact that no drawing of the fibres is produced in this operation.

15 In the drawing frame all the slivers are drawn together and practically no breakage of the web occurs in this operation. A draft of, say, 10 to 25, or over, can be obtained in the drawing frame, the machine being adjusted according to the principles followed in operating drawing frames of the ordinary types. For example, the spread between the drawing rolls and the pressure rolls will depend upon the weight 25 of the entering lap, the nature of the fibre, etc. With this process, however, a lap formed of, say, fourteen, sixteen or eighteen slivers, gives a normal doubling with a single drawing operation. If one of the 30 stop motion spoons should not work properly, the resulting variation in the lap would be only one-fourteenth, one-sixteenth, or one-eighteenth, according to the number of slivers used. The invention therefore produces more uniform work, and effects a substantial increase in efficiency in the preparation of cotton for the spinning operation.

35 While I have herein shown and described the preferred constructions, it will be evident that the invention may be embodied in other forms without departing from the spirit or scope thereof.

Having thus described my invention, what I desire to claim as new is:

1. That improvement in the process of preparing cotton fibre for spinning which consists in arranging a series of slivers side by side to form a web, winding said web to form a lap, subsequently unwinding said web, drawing the web, and condensing the 50 drawn web to form a roving or sliver.

2. That improvement in the process of preparing cotton fibre for spinning which consists in winding a series of parallel slivers together, without drawing, to form 55 a lap, subsequently unwinding said slivers in unison and drawing them simultaneously.

3. In a drawing frame, the combination of means for supporting a lap for the unwinding therefrom of the web of which it is composed, rolls for drawing said web, a web guide between said means and rolls having converging sides, and an additional web guide at the opposite end of the machine having converging sides.

4. In a drawing frame, the combination of means for supporting a lap for the unwinding therefrom of the web of which it is composed, rolls for drawing said web, and a feed roll to engage said lap and unwind 70 said web, said feed roll having collars at opposite ends of the feeding surface thereof to limit the endwise movement of the lap.

5. That improvement in the process of preparing cotton fibre for spinning which 75 consists in winding a series of parallel slivers together side by side, without drawing, to form a lap, subsequently unwinding said slivers in unison, drawing said slivers simultaneously and thereby producing a 80 web, and condensing the drawn web to form a sliver or roving.

MARTIN AUGUSTE ROTH.
